PRINTING PLATE COOLER

Charley Bush, Akron, Ohio

Application November 1, 1939, Serial No. 302,459

4 Claims. (Cl. 62—11)

This invention relates to an apparatus adapted to cool printing plates immediately after the casting thereof to expedite the handling and use of the same.

It is particularly aimed to provide novel means wherein the cooling fluid is dispersed evenly, in a spray and without undue or harmful force against the plates, and more specifically, by means of a novel discharge bell and co-acting gauze or screen.

A further object is to provide a novel structure wherein the plates to be cooled are contained within a base or main section which has a hood mounted thereover as a closure and contains the discharge means for the cooling fluid.

I further aim to provide a construction wherein in the cooling fluid such as water, is augmented by air under pressure or steam to give it the proper force, a construction wherein novel ventilation is afforded for undue heat and steam and a construction for the effective collection of surplus water or fluid.

The more specific objects and advantages will become apparent from a consideration of the description following taken in connection with accompanying drawings illustrating an operative embodiment.

In said drawings:

Figure 1 is a view of the apparatus, in side elevation;

Figure 2 is a view of the same apparatus and in end elevation;

Figure 3 is a vertical sectional view taken on the line 3—3 of Figure 2, and

Figure 4 is a vertical sectional view taken on the line 4—4 of Figure 1.

Referring specifically to the drawings wherein like reference characters designate like or similar parts, the apparatus generally comprises a main or base section A and a hood or cover section B, said sections being connected together by hinge means at 10 movable on a horizontal axis so that the hood B may be raised and lowered for the insertion or removal of a tray or container 11 in which the printing plates after casting are placed for cooling. For example, such printing plates may be those cast from electro-type metal in electrotype foundries.

Applicant's invention includes the base section A which has four corner posts 12 connected at their tops by transverse members 13, on all of which, a table 14 is disposed. On the table 14, a rectangular frame 15 is fastened and on the inner surface thereof battens or strips 16 are fastened upon which the aforesaid tray 11 re-

movably rests. Through the said frame 15 openings or vents 17 are provided for the escape of steam and dissipation of heat.

Supported on said base section A is an inlet or supply pipe 18 for cooling fluid such as water and an inlet or supply pipe for a pressure medium to cause travel of the water through the apparatus at the desired pressure, as at 19. Such pressure medium may be compressed air or steam. Said pipes respectively have fittings 20 and 21 whereby they may be connected to their sources of supply and such pipes have regulating and cut-off valves therein as at 22 and 23.

Said pipes 18 and 19 are joined together by piping as at 24 constituting a mixing chamber 15 for such water and pressure medium. The water under pressure is adapted to be supplied to the hood and used to cool the printing plates within the tray 11. Water which drains therefrom onto the table 14, will flow into a well 25 supported from below by a board or bracket 26, connected to one of the transverse braces 27 employed for the legs or corner posts 12. Braces 28 may also be secured to said corner posts at the same elevation as those at 27.

The hood section B is generally frusto-pyramidal inasmuch as the upper portion 28' of its main wall 29 extends upwardly and inwardly. A bar 30 is fastened transversely of the wall 29 adjacent the top thereof and a bolt or other fastening 31, suspends a bell shaped spreader 32 therefrom which has a metallic or other wire fabric, screen or gauze 33 fastened across the lower end thereof. A discharge nozzle 34 extends through the gauze 33 centrally thereof, to discharge the cooling fluid against the inner surface of the bell. Such nozzle 34 extends from a pipe 35 fastened in the wall 29 and which has a right angular portion 36, exteriorly of the hood extending rearwardly toward the hinge 10. On the free end 40 of the pipe 36 and the mixer pipe 24, the opposite ends of a flexible hose 37 are removably connected. Such a flexible hose, enables movement of the hood on its axis without dismantling any of the parts of the supply piping or conduit for the cooling fluid.

Within the main wall 29 of the hood, battens 38 are fastened and a rectangular frame 39 is secured thereto which has upper and lower wire fabric, screen or gauze of metal or other suitable material, extending thereacross.

As a result of the construction described, the tray 11 may be readily applied or removed from the structure with the hood B in open position, such tray containing the castings or printing

plates to be cooled. The water is supplied through the pipe 18 and steam or compressed air supplied through the pipe 19, the valves 22 and 23 being operated to control the same. Such water 5 and air or steam mixes in the piping 24 and passes therefrom through the hose 31, pipe 36, pipe 35 and nozzle 34, discharging against the upper surface of the interior of the bell 32, thereby being spread and dripping downwardly and 10 evenly through the successive screens, gauze or wire fabric at 33, 40 and 41 and onto the plates or castings within the tray. It will be realized that the screens 33, 40 and 41, in combination with the bell, effectively spread the cooling fluid, caus- 15 ing it to spread or flow evenly against the castings, to avoid too sudden chilling of the latter or concentration of the chilling action at any particular point. Steam and pressure and heat 20 will be dissipated through the ports 17 and similar ports 17a provided in the lower edge of the wall 29.

Surplus water will drain onto the table 14 and pass into the well 25, from which the same may 25 drain or be removed in any appropriate manner by connection at an outlet 25a thereof.

At the top of section B a removable slide 42' may be mounted in grooves 43 of a frame 44, enabling access to the bell 32 and adjacent parts 30 from above.

Various changes may be resorted to provided they fall within the spirit and scope of the invention.

I claim as my invention:

35 1. Apparatus for cooling printing plates or the like, said apparatus comprising a base section, means therein to hold the printing plates, a cover section movable relatively to the base section, means to discharge cooling fluid into the cover 40 section, means between the first and second means to cause spreading of the cooling fluid and dripping thereof onto the printing plates, comprising a bell against which the fluid is discharged, a perforated member at the discharge side of the 45 bell, and perforated means within the cover section substantially coextensive with the zone of reception of the printing plates.

2. Apparatus for cooling printing plates or the like, said apparatus comprising a base section, 50 means therein to hold the printing plates, a cover

section movable relatively to the base section, means to discharge cooling fluid into the cover section, means between the first and second means to cause spreading of the cooling fluid and dripping thereof onto the printing plates, comprising a bell against which the fluid is discharged, a perforated member at the discharge side of the bell, perforated means within the cover section substantially coextensive with the zone of reception of the printing plates, said means to supply fluid including a flexible connection to enable movement of the closure section, said means including two pipes one for the supply of fluid and one for the supply of a pressure medium to said fluid. 15

3. Apparatus for cooling printing plates or the like, said apparatus comprising a base section, means therein to hold the printing plates, a cover section movable relatively to the base section, means to discharge cooling fluid into the cover 20 section, means between the first and second means to cause spreading of the cooling fluid and dripping thereof onto the printing plates, comprising a bell against which the fluid is discharged, a perforated member at the discharge side of the bell, 25 perforated means within the cover section substantially coextensive with the zone of reception of the printing plates, said means to supply fluid including a flexible connection to enable movement of the closure section, said means including two pipes one for the supply of fluid and one for the supply of a pressure medium to said fluid, the structure adjacent the junction of the closure section and base section having openings for the 30 escape of steam and heated air, and the base section having openings for the escape of steam and heated air, and a well to catch surplus cooling fluid carried by the base section, and displaceable closure means for the top of the closure section. 35

4. Apparatus for cooling printing plates or the like, said apparatus comprising a base section, means therein to hold the printing plates, a cover section movable relatively to the base section, means to discharge cooling fluid into the cover section, a bell against which said cooling fluid 40 is discharged, and a perforated means below said bell and above said second means to cause spreading of the cooling fluid and dripping thereof onto the printing plates. 45
